UNITED STATES PATENT OFFICE.

ALFRED H. S. SWAN, OF ROCHESTER, NEW YORK, ASSIGNOR TO ROCHESTER STAMPING COMPANY, OF ROCHESTER, NEW YORK, A CORPORATION OF NEW YORK.

DESIGN FOR A CRUMB-SCRAPER OR SIMILAR ARTICLE.

40,459.

Specification for Design.

Patented Jan. 25, 1910.

Application filed November 17, 1909. Serial No. 528,631. Term of patent 7 years.

To all whom it may concern:

Be it known that I, ALFRED H. S. SWAN, a citizen of the United States, residing at Rochester, in the county of Monroe and State of New York, have invented a new, original, and ornamental Design for Crumb-Scrapers and Similar Articles, of which the accompanying drawing is a representation.

The figure is a plan view of a crumb scraper showing my new design.

I claim:

The ornamental design for a crumb scraper, or similar article, as shown.

ALFRED H. S. SWAN.
